N-HYDROXYCARBANILIDES AND THEIR USE AS BACTERICIDES AND FUNGICIDES

Peggy Pamela Hoffman, Somerville, and William Baptist Hardy, Bound Brook, N.J., assignors to American Cyanamid Company, New York, N.Y., a corporation of Maine
 No Drawing. Filed Aug. 8, 1961, Ser. No. 129,999
 4 Claims. (Cl. 260—553)

This invention relates to new germicides and to detergent compositions containing these germicides. More specifically this invention relates to N-hydroxycarbanilides having at least two substituents of the group consisting of halogen and trihalomethyl, and which may be further substituted by halogen, nitro, lower alkyl or lower alkoxy radicals; and to non-ionic and anionic detergent compositions containing them.

In recent years, increased attention has been given to the development of textile purifying finishes. These finishes inhibit the growth, and reduce the number of microorganisms on the material. These purifying finishes, when applied to articles of clothing worn close to the body, are also helpful in preventing the development of body odors.

A satisfactory purifying finish should be durable and active at low concentrations against a broad spectrum of microorganisms. It should be non-toxic and non-allergenic. It should not have the tendency to sensitize the wearer of the textile fabric to the material of the finish. It should not have the property of allowing strains of bacteria to develop which are resistant to the antibacterial agent of the finish. It should impart little or no color to the fabric and should be stable with respect to color and activity for many months under storage and shipping conditions. It should be resistant to the conditions used in laundering and dry cleaning. It should cause little or no modification of the hand of the textile. It should be substantive to the fiber. It should be compatible with dyes and resins with which it may be in contact on the textile.

Various textile purifying finishes containing anti-bacterial substances such as hexachlorophene, tetrachlorophene, quaternary ammonium compounds such as dimethyl benzyl ammonium chloride, organo-metallic complexes of mercury, copper and silver, and others have been used but are for the most part non-durable and unsatisfactory in other respects, especially in their inability to exhaust from a laundry bath.

Substantivity on the fiber and durability of the antibacterial action are two of the most important desirable properties. Without substantivity on the fiber the germicide is merely a coating to be rubbed or washed off by the first treatment to which it is subjected. Substantivity for the fiber is, therefore, one of the main bases upon which durability rests. However, durability must also be a function of the stability of the compound itself to oxidation by air, degradation by light, heat and the like.

Especially important is the property of substantivity under laundering conditions and especially of exhaustion from such a laundry bath in the same way that a dye exhausts from a dye bath. If a germicide is to have the widest utility as a textile finish, the best place to use it is in the regular laundering, whether in the home or in a hospital or a commercial laundry. Such a germicidal finish builds up in concentration on the fiber with further washing since new applications of germicide are made during such further washing.

This invention is based on the discovery of a new class of compounds, defined above, the members of which have high germicidal action and are substantive to fabrics. The

new compounds may be represented by the structural Formula I:

wherein the X₂, X₃, X₄, X₅, X₆, Y₂, Y₃, Y₄, Y₅ and Y₆ are individually either hydrogen, halogen (especially chlorine and bromine), nitro, lower alkyl, lower alkoxy and trihalomethyl (e.g. trichloromethyl and especially trifluoromethyl), at least two of the "X" and "Y" radicals being halogen or trihalomethyl. Within the class of compounds constituting this invention those compounds which have halo and/or trihalomethyl groups in both phenyl moieties are preferred since they generally show greater germicidal activity than the analogs which are substituted in only one phenyl moiety. It has also been found that those compounds having at least one 3,4-dichlorophenyl radical, 3,4,5-trichlorophenyl radical, and particularly a 3,5-dichlorophenyl radical or a 3-trifluoromethylphenyl radical show higher activity than those in which the chloro radicals are in the 2- or the 6-positions of the phenyl moieties.

The new compounds of this invention may be prepared by reacting a phenyl isocyanate with an N-phenylhydroxylamine in the presence of a non-polar halogenated organic solvent (e.g. chloroform) or an aromatic monocyclic hydrocarbon (e.g. benzene, toluene and xylene) at ambient temperatures using approximately equimolar proportions of the reactants. The reaction may be represented by the following equation in which X₂, X₃, X₄, X₅, X₆, Y₂, Y₃, Y₄, Y₅ and Y₆ are as hereinbefore defined.

45

50

55

As examples of suitable phenyl isocyanates which may be used, these may be named inter alia: phenyl isocyanate, 2-, 3- and 4-chlorophenyl isocyanate, 2,3-, 2,5-, 3,4- and 3,5-dichlorophenyl isocyanate, 3-(trifluoromethyl)phenyl isocyanate and 3,5-bis(trifluoromethyl)phenyl isocyanate, 2-, 3- and 4-bromophenyl isocyanate, 3,4- and 3,5-dibromophenyl isocyanate, 3,4,5-trichlorophenyl isocyanate, 3- and 4-nitrophenyl isocyanate, 2-, 3- and 4-methylphenyl isocyanate, 3-(trifluoromethyl)-4-bromophenyl isocyanate, 3-(trifluoromethyl)-4-chlorophenyl isocyanate and 4-methoxyphenyl isocyanate.

60

65

70

As examples of suitable N-phenylhydroxylamines which may be used, these may be named inter alia: N-phenylhydroxylamine, N-(2-chlorophenyl)hydroxylamine, N-(4-chlorophenyl)hydroxylamine, N-(3-chlorophenyl)hydroxylamine, N-(4-iodophenyl)hydroxylamine, N-(2,5-dichlorophenyl)hydroxylamine, N-(3,4-dichlorophenyl)hydroxylamine, N-(3,5-dichlorophenyl)hydroxylamine, N-3-(trifluoromethyl)phenyl hydroxylamine, N-3-(trichloromethyl)phenyl hydroxylamine, N-(3,4,5-trichlorophenyl)hydroxylamine, N-(2-methyl-3-chlorophenyl)hydroxylamine, N-(2-methyl-5-chlorophenyl)hydroxylamine, and N-(2-methyl-4,5-dichlorophenyl)hydroxylamine.

The germicides of this invention when padded or "exhaust dyed" on cloth, show such germicidal activity that *Staphylococcus aureus* and *E. coli*, for example, are inhibited not only where in contact with the treated cloth, but in an area beyond. After many washing cycles, the

padded fabric still shows activity against *Staphylococcus aureus* and *E. coli* in contact with the cloth.

It is an important advantage of the germicides of this invention that they become attached to fibers when applied from an aqueous bath at only slightly elevated temperatures. They have notably strong affinity for cotton and may be applied to cotton in temperatures as low as those used in laundry procedures. They may also be applied at the higher temperatures normally used in the dyeing of cotton, i.e. near the boil. These compounds are thus particularly suitable for hospital and home use, where it is more difficult to attain the temperatures close to the boil that are used in a dyeing mill. In addition to cotton, the germicides of this invention have affinity for other fibers such as nylon, cellulose acetate and the like when applied from laundry bath.

The compounds of this invention are compatible with non-ionic and anionic detergents. This is a further advantage of this invention since the germicide can be applied from a detergent bath such as is used in laundering in the home or in a hospital. Germicidal compositions including the compounds of this invention in admixture with alkyl aryl sulfonates (anionic detergents) are especially suitable compositions for the application for durable finishes to cotton and other fibers especially during home or commercial laundering procedures. During the process of laundering, the germicide becomes attached to the fiber and the fiber is thus rendered sterile for long periods. A detergent composition having from about 0.01 to 5.0% germicide on the weight of the detergent is an effective composition for this purpose.

The organic anionic detergents which may be used in the compositions of this invention include alkali metal fatty acid soaps and, in addition, the well known surface-active alkali metal sulfonates and sulfates. The latter may be employed as the sole detergent base or in admixture with alkali metal fatty acid soaps, as for example, 1 part of fatty acid soap to 0.5 to 2 parts by weight of the surface-active alkali metal sulfonates or sulfates or mixtures thereof. A preferred group of this class is the long chain alkyl aryl sulfonates, i.e., those wherein the alkyl group is straight or branched in structure and contains from 8 to 22 carbon atoms, but preferably 10 to 16 carbon atoms, examples of which being octyl, decyl, dodecyl, pentadecyl, hexadecyl, octadecyl, mixed long chain alkyl derived from long chain fatty acids such as the lauryl radical, cracked parrafin wax olefins, polymers of low mono-olefins such as propylene tetramer and the like, and wherein the aryl radical is derived from benzene, toluene, xylene, phenol, the cresols, naphthalene and the like. Specific examples of such comprise sodium decylbenzenesulfonate, sodium dodecylbenzenesulfonate, sodium laurylbenzenesulfonate, and sodium hexadecylbenzenesulfonate. Other sulfonate surface active agents are contemplated also, as for example, the long chain alkyl sulfonates such as sodium hexadecyl sulfonate and sodium octadecyl sulfonate.

The well known sulfate detergents having 12 to 26 carbon atoms and particularly those having an alkyl radical of about 8 to 22 carbon atoms may be employed as an anionic detergent in the compositions of this invention. Such detergents include sulfuric acid esters of polyhydric alcohols incompletely esterified with fatty acids, e.g. sodium cocoanut oil monoglyceride monosulfate, sodium tallow diglyceride monosulfate, the pure and mixed alkyl sulfates, and higher sulfates such as sodium lauryl sulfate and sodium cetyl sulfate.

Additional anionic surface active sulfonates and sulfates contemplated by this invention are the sulfonated and sulfated alkyl acid amides such as Igepon T of the formula

The sulfated and sulfonated esters such as Igepon AT of the formula

in which R is an alkyl radical containing from 12-18 carbon atoms, the sodium salt of the sulfonic acid derivative of a dialkyl dicarboxylate, disodium sulfosuccinate monoamide such as

and the like.

In addition to the anionic surface active agents, non-ionic surface active agents may be used as the base for germicidal compositions of our invention. The non-ionic surface active agents which may be used are viscous liquid, wax-like, water soluble surface active substances containing a polyglycol ether group of the structure

15

in which Z_1 and Z_2 are hydrogen or a short chain alkyl, p is an integer greater than three and Z is a residue of a monomeric organic compound having an active hydrogen, as for example, an alcohol, a phenol, an amide, a primary amine, a secondary amine, a carboxylic acid or the like. These non-ionic detergents are well known (e.g. U.S. 1,970,578 and U.S. 2,213,477) and may be typified by polyalkylene oxide derivatives (e.g. polyethylene oxide, polypropylene oxide, polybutylene oxide) of water-insoluble higher fatty acids, such as lauric, oleic, palmitic and stearic and the like, or mixtures thereof such as the mixtures of fatty acids obtained from animal and vegetable fats and oils and by the oxidation of petroleum fractions such as parafin wax. They may also be exemplified by the polyalkylene oxide derivatives of such water-insoluble organic hydroxy compounds as higher aliphatic compounds (i.e. the alcohols corresponding to the fatty acids specified above or mixtures thereof) phenols, particularly alkyl phenols containing at least six alkyl carbon atoms such as isooctyl, trisopropyl, nonyl, dodecyl, octadecyl phenols or naphthols, or of aralkyl alcohols such as benzyl alcohol, cinnamyl alcohol and the like. They may also be exemplified by the polyalkylene oxide derivatives of such amines as stearyl, lauryl, dicyclohexyl, dibutyl amine and the like. A particularly useful non-ionic detergent is that obtained by condensing one mole of tall oil with 5-15 moles of ethylene oxide.

45

It is an additional advantage of those compounds which are effective against the gram positive bacteria, e.g., *Staphylococcus aureus*, that they are effective against the other gram positive bacteria which break down perspiration into odoriferous products.

50

The germicides of this invention may also be applied to surfaces. This can be done in the form of a solution in dimethylformamide containing 0.01 to 1.0% on the weight of the germicide. In addition, more concentrated solutions may be added to cleaning materials, floor waxes and the like to give a final concentration of 0.01 to 1.0% germicide for application to a surface. Such an application produces a surface which is durably germicidal.

55

This invention can be illustrated by the following examples in which parts are by weight unless otherwise specified.

EXAMPLE 1

3,3'-dichloro-N-hydroxycarbanilide

65

70

To a solution of 3.59 parts of N-(3-chlorophenyl)-hydroxylamine in 150 parts of chloroform are added 3.84 parts of 3-chlorophenyl isocyanate. The resulting slurry is stirred for two hours at room temperature and then the precipitate is filtered off. After drying in vacuo, the product is purified by crystallization from aqueous methanol. The almost white crystals melt at about 150-151° C.

75

This compound shows more than a three fold increase in activity by standard agar dilution procedures as compared with the non-N-hydroxylated analog, against *Staph. aureus*. It shows a correspondingly greater activity when padded from a dimethylformamide solution onto cotton against *Staph. aureus* and *E. coli*.

EXAMPLE 2

3',5'-dichloro-N-hydroxycarbanilide

A solution of 9.40 g. of 3,5-dichlorophenyl isocyanate in 150 parts of chloroform is added to a solution of 5.46 parts of N-phenylhydroxylamine in 300 parts of chloroform. The resulting slurry is stirred at room temperature for two hours. The precipitate is filtered off, dried at room temperature and recrystallized from benzene to give a white product melting at about 151-152° C.

EXAMPLE 3

3-trifluoromethyl-3',4'-dichloro-N-hydroxycarbanilide

To a solution of 14.23 parts of 3-(trifluoromethyl)-nitrobenzene in 65 parts of ethanol is added a solution of 1.6 parts of ammonium chloride in 20 parts of water. While stirring at the reflux temperature, zinc dust is slowly added (about 28 parts) until the reaction mixture becomes colorless. After the reaction mixture has been cooled and the reaction vessel flushed with nitrogen, 90 parts of benzene are added, and the reaction mixture is well stirred. The benzene containing the reaction product, namely N-[3-(trifluoromethyl)-phenyl]hydroxylamine, is separated and dried with anhydrous sodium sulfate.

The above solution of N-[3-(trifluoromethyl)-phenyl]hydroxylamine in benzene is added to a solution of 6.6 parts of 3,4-dichlorophenyl isocyanate in 45 parts of benzene. After stirring at room temperature for two hours, the benzene is removed by distillation in vacuo. The residue is slurried with chloroform and filtered to obtain the product which, after crystallization from aqueous methanol, appears as almost white crystals melting at about 148-149° C.

The product shows high activity against *Staph. aureus* and *E. coli* when padded onto cotton (1% on the weight of the fabric) from a solution in dimethylformamide (DMF). The non-hydroxylated analog shows no significant activity under the same conditions.

EXAMPLE 4

3,3',4,4' tetrachloro-N-hydroxycarbonilide

A solution of 1.6 parts of ammonium chloride in 20 parts of water is added to a solution of 14.6 parts of 3,4-dichloronitrobenzene in 65 parts of ethanol. While stirring at the reflux temperature, zinc dust is slowly added (about 28 grams) until the reaction mixture becomes colorless. After the removal of the alcohol by distillation under vacuo, the residue is stirred with 90 parts of benzene and filtered. The benzene filtrate containing the product, namely N-(3,4-dichlorophenyl)hydroxylamine, is dried with anhydrous sodium sulfate.

The solution of N-(3,4-dichlorophenyl)hydroxylamine in benzene is added to a solution of 8.45 parts of 3,4-dichlorophenyl isocyanate in 40 parts of benzene. After stirring the reaction mixture at room temperature for two hours, the benzene is removed under vacuo and the

residue slurried with chloroform. The product obtained by filtration, and recrystallized from aqueous methanol, melts at about 140-141° C. with decomposition.

EXAMPLE 5

The above product prepared by the procedure of Example 4 using the corresponding phenyl isocyanate and N-phenylhydroxylamine and when tested by the conventional agar dilution method against *Staph. aureus* shows more than seven times the activity of the non-hydroxylated derivative tested by the same method.

Example 6

The above product prepared by the procedure of Example 2 using the corresponding phenyl isocyanate and N-phenylhydroxylamine and when tested by the conventional agar dilution method against *Staph. aureus* shows more than four times the activity of the non-hydroxylated derivative tested by the same method.

EXAMPLE 7

This product obtained by the reaction of 3-(trifluoromethyl)phenyl isocyanate and N-(3,4,5-trichlorophenyl)hydroxylamine, prepared from 3,4,5-trichloronitrobenzene under the conditions of Example 4, having a melting point of about 164° C. shows good activity against *Staph. aureus* when padded onto cotton (1% on the weight of the fabric) from a solution in DMF and also when exhausted onto cotton from 0.5% and 0.1% aqueous solutions containing "Fab" (a non-ionic detergent) on the weight of the fabric. This compound is extremely active against *S. aureus* in the agar dilution test.

EXAMPLE 8

This product prepared by the reaction of 3-chlorophenyl isocyanate and N-(3,5-dichlorophenyl)hydroxylamine, prepared from 3,5-dichloronitrobenzene under the conditions of Example 4, having a melting point of about 179° C. when padded onto cotton (1% on the weight of the fabric) from a solution in DMF shows good activity against *E. coli* as compared to the non-N-hydroxylated analog which has negligible activity under the same conditions.

EXAMPLE 9

This product prepared by the reaction of p-chlorophenyl isocyanate and N-(3,4,5-trichlorophenyl)hydroxylamine, prepared from 3,4,5-trichloronitrobenzene under the conditions of Example 4, having a melting point of 198° C. shows good activity against *Staph. aureus* in the agar dilution method and against *Staph. aureus* and *E.*

coli when applied to cotton by both the padding and exhaustion procedures as described hereinbefore.

EXAMPLE 10

This product prepared by the reaction of 3,4-dichlorophenyl isocyanate and N-(p-chlorophenyl)hydroxylamine by the reaction shown in Example 2 has a melting point of about 150-151° C. and is active against *Staph. aureus* and *E. coli* when applied to textiles and against *Staph. aureus* in the agar dilution test.

EXAMPLE 11

This product prepared by the reaction of 3,5-dichlorophenyl isocyanate and N-(3,5-dichlorophenyl)hydroxylamine having a melting point of 184° C. is highly active against *Staph. aureus* and *E. coli*.

EXAMPLE 12

This product prepared by the reaction of 3,5-dichlorophenyl isocyanate with N-(p-chlorophenyl)hydroxylamine under the conditions of Example 2 having a melting point of 155-156° C. shows activity against *E. coli* when padded onto cotton fabric (1% on the weight of the fabric) from a solution in DMF. The corresponding non-hydroxylated analog shows no significant activity under the same conditions. In the agar dilution test the product of this example is more than four times as active as the corresponding non-hydroxylated analog against *Staph. aureus*.

EXAMPLE 13

This compound prepared by the reaction of 3-(trifluoromethyl)phenyl isocyanate with N-(p-chlorophenyl)hydroxylamine under the conditions of Example 2 having a melting point of about 125° C. when padded onto cotton (1% on the weight of the fabric) from a solution in DMF shows high activity against *Staph. aureus* as compared to the corresponding non-hydroxylated compound which shows a negligible activity under the same conditions.

EXAMPLE 14

This product prepared by the reaction of 3,4,5-trichlorophenyl isocyanate with N-(3,4,5-trichlorophenyl)hydroxylamine prepared from 3,4,5-trichloronitrobenzene under the conditions of Example 4, having a melting point of about 200-210° C. is active against *Staph. aureus* when exhaust dyed onto cotton from both 0.1% and 0.5% (on

weight of the fabric) aqueous solutions containing a non-ionic detergent.

EXAMPLE 15

This product prepared by the reaction of 3,4,5-trichlorophenyl isocyanate and N-[3-(trifluoromethyl)phenyl]hydroxylamine, prepared from 3-(trifluoromethyl)nitrobenzene under the reaction conditions of Example 4, having a melting point of about 170-172° C. shows good activity against *Staph. aureus*.

EXAMPLE 16

This product prepared by the reaction of p-bromophenyl isocyanate with N-(3,5-dichlorophenyl)hydroxylamine, prepared from 3,5-dichloronitrobenzene under the conditions of Example 4, having a melting point of 181-182° C. is active against *Staph. aureus* and *E. coli* in the cotton padding test hereinbefore described.

EXAMPLE 17

This product prepared by the reaction of 3-nitrophenyl isocyanate and N-(3,5-dichlorophenyl)hydroxylamine, prepared from 3,5-dichloronitrobenzene under the reaction conditions of Example 4, having a melting point of about 189° C. shows activity against *Staph. aureus* and *E. coli* when padded onto cotton fabric (1% on the weight of the fabric) from a solution in DMF.

A corresponding p-nitro isomer having a melting point of 182-183° C. is highly active against *Staph. aureus* in the agar dilution test.

EXAMPLE 18

This product prepared by the reaction of p-methoxyphenyl isocyanate and N-(3,5-dichlorophenyl)hydroxylamine, prepared from 3,5-dichloronitrobenzene by the procedure of Example 4, having a melting point of 170-171° C. is active against *Staph. aureus* in the cotton padding test.

The product prepared from the corresponding p-methoxyphenyl isocyanate having a melting point of 165° C. is likewise an active germicide under the same test conditions.

EXAMPLE 19

The carbanilide of the above formula from 3-(trifluoromethyl)-4-bromophenyl isocyanate and N-(3,4-dichlorophenyl)hydroxylamine prepared from 3,4-dichloronitrobenzene by the procedure of Example 4, having a melting point of about 167° C. shows greater activity

than the corresponding non-hydroxylated analog against *Staph. aureus* when padded onto the fabric.

EXAMPLE 20

This product prepared by the reaction of 3,5-bis(trifluoromethyl)phenyl isocyanate and N-(3,5-dichlorophenyl)hydroxylamine prepared from 3,5-dichloronitrobenzene under the reaction conditions of Example 4, having a melting point of about 188-189° C. shows more than a 15 fold increase in activity against *Staph. aureus* in the agar dilution test as compared to the corresponding nonhydroxylated analog.

EXAMPLE 21

This product obtained by the reaction of 3-(trifluoromethyl)-4-chlorophenyl isocyanate with N-[3-(trifluoromethyl)phenyl]hydroxylamine prepared from 3-(trifluoromethyl)nitrobenzene by the reaction of Example 4, having a melting point of 147-148° C. shows good activity against *Staph. aureus* and *E. coli* when padded onto cotton fabric (1% on the weight of the fabric) from a solution in DMF.

EXAMPLE 22

This product obtained by the reaction of 3-(trifluoromethyl)-4-chlorophenyl isocyanate with N-(3,4-dichlorophenyl)hydroxylamine, prepared from 3,4-dichloronitrobenzene by the reaction in Example 4, having a melting point of 161-162° C. shows very good activity against *E. coli* when padded on cotton fabric as compared with negligible activity by the corresponding compound without the hydroxyl group.

EXAMPLE 23

This compound obtained by the reaction of 3-(trifluoromethyl)-4-bromophenyl isocyanate with N-(3,5-dichlorophenyl)hydroxylamine, prepared from 3,5-dichloronitrobenzene under the conditions of Example 4, having a melting point of 175-176° C. shows good activity against *Staph. aureus* when padded on cotton fabric. In the agar dilution test this derivative shows about four times the activity against *Staph. aureus* of the non-hydroxylated derivative.

EXAMPLE 24

This product obtained by the reaction of 3-(trifluoromethyl)-4-bromophenyl isocyanate with N-(3,4,5-trichlorophenyl)hydroxylamine, prepared from 3,4,5-trichloronitrobenzene by the reaction of Example 4, having

5

a melting point of 190° C. shows excellent activity in agar against *Staph. aureus*.

10

EXAMPLE 25

This product obtained by the reaction of 2,3-dichlorophenyl isocyanate with N-(3-chlorophenyl)hydroxylamine under the reaction conditions of Example 2 having a melting point of 161-162° C. is active against *Staph. aureus* when padded on cotton and in the agar dilution test as compared with insignificant activity against *Staph. aureus* of the non-hydroxylated analog.

EXAMPLE 26

This derivative obtained by the reaction of 2,5-dichlorophenyl isocyanate with N-(3-chlorophenyl)hydroxylamine, having a melting point of 158-159° C., as compared with the non-hydroxylated analog shows good activity in the agar dilution test and when padded onto cotton fabric.

EXAMPLE 27

This derivative obtained by the reaction under the conditions of Example 2 of 3,4-dichlorophenyl isocyanate with N-(2-methyl-3-chlorophenyl)hydroxylamine having a melting point of 179° C. shows good activity against *Staph. aureus* when padded onto cotton fabric.

EXAMPLE 28

This derivative prepared by the reaction of 3-(trifluoromethyl)phenyl isocyanate with N-[3-(trifluoromethyl)phenyl]hydroxylamine prepared from 3-(trifluoromethyl)nitrobenzene by the procedure of Example 4, having a melting point of about 127° C. shows very good activity against *E. coli* when padded on cotton as compared to insignificant activity of non-hydroxylated analog. It also shows three times the activity in the agar dilution test against *Staph. aureus*.

EXAMPLE 29

The product obtained by the reaction of 3,5-dichlorophenyl isocyanate with N-(4-iodophenyl)hydroxylamine under the reaction conditions of Example 2 is active against *Staph. aureus*.

EXAMPLE 30

The product obtained by the reaction of 3,5-dichlorophenyl isocyanate with N-[3-(trichloromethyl)phenyl]hydroxylamine under the reaction conditions of Example 2 is active against *Staph. aureus*.

11

hydroxylamine by the reaction conditions of Example 4 is active against *Staph. aureus*.

EXAMPLE 31

This derivative obtained by the reaction of 3,4-dichlorophenyl isocyanate with N-(3,5-dichlorophenyl)hydroxylamine, prepared from 3,5-dichloronitrobenzene under the conditions of Example 4, shows good activity against *Staph. aureus* when padded on cotton fabric.

EXAMPLE 32

This derivative obtained by the reaction of 3,4,5-trichlorophenyl isocyanate with N-(3,5-dichlorophenyl)hydroxylamine, prepared from 3,5-dichloronitrobenzene under the conditions of Example 4, shows excellent activity against *Staph. aureus* in the agar dilution test.

EXAMPLE 33

This derivative obtained by the reaction of 3-(trifluoromethyl)phenyl isocyanate with N-(3,5-dichlorophenyl)hydroxylamine, prepared from 3,5-dichloronitrobenzene under the conditions of Example 4, shows very good activity against *Staph. aureus* when padded on cotton fabric.

We claim:

1. An N-hydroxy carbanilide wherein the non-hydroxylated nitrogen atom is unsubstituted and the phenyl moieties of the carbanilide are substituted by "m" halo and "n" trihalomethyl groups wherein "m" is an integer less than eleven and "n" is an integer less than five and

5 the total of "m" and "n" is greater than one and less than eleven wherein the halo groups have an atomic number less than 54 and the remaining valences of the phenyl moieties are satisfied by members selected from the group

5 consisting of hydrogen, nitro, lower alkyl and lower alkoxy.

2. The compound of the formula

3. The compound of the formula

4. The compound of the formula
